UNITED STATES PATENT OFFICE.

ARTHUR REGINALD ANGUS, OF BRIGHTON, ENGLAND.

ELECTRIC CONTROL OF RAILWAY TRAINS OR VEHICLES.

1,414,999.

Specification of Letters Patent.

Patented May 2, 1922.

Application filed September 23, 1921. Serial No. 502,682.

To all whom it may concern:

Be it known that I, ARTHUR REGINALD ANGUS, a subject of the King of Great Britain and Ireland, and a resident of Brighton, 5 in the county of Sussex, England, have invented certain new and useful Improvements in or Relating to the Electric Control of Railway Trains or Vehicles, of which the following is a specification.

10 This invention relates to apparatus for the electrical control of trains or vehicles (hereinafter referred to as trains) on joining portions of railway tracks.

In apparatus for this purpose according 15 thereto the condition of the joining track portions as to occupation by a railway vehicle and integrity of their rails is adapted to determine the condition as to energization of a first set of electro-responsive devices 20 which are connected to rails of the track portions respectively and each of which is adapted to be energized by electricity conveyed through the rails to which it is connected and to be de-energized by the interruption 25 of the passage of the said electricity and also by the short-circuiting of the said electricity therefrom as by conductively connected wheels of a railway vehicle, and each rail portion joining opposite sides of a said 30 track portion is interrupted by insulation bridged by one of a second set of electro-responsive devices each of which is adapted to be de-energized by the failure of the corresponding insulation, each of the said electro-responsive devices being adapted when 35 de-energized to prevent a train from being allowed to pass along any of the joining track portions.

For controlling the making of a road by 40 a signalman there is in conjunction with a manual road-making means provided an electromagnetic locking means adapted unless energized to prevent the road-making means from being so operated as to permit 45 the passage of a train over the said road and adapted to depend for its energization upon the energization of the aforesaid electro-responsive devices. In order to make the energization of the electromagnetic locking 50 means dependent on the condition of the track portion next in advance of the road,

an electro-responsive device corresponding in function to those of the aforesaid first set is provided for the last mentioned track portion and its energization made essential 55 to the energization of the electromagnetic locking means.

For testing a road there is provided switching means adapted to enable a signalman to cause electricity for energizing the 60 aforesaid electro-responsive devices to be transmitted, and to interrupt such transmission of electricity, to the rails to which the said devices are connected; and for testing the condition of the track portion next in 65 advance of the road the last mentioned track portion is provided with an electro-responsive device connected to the rails thereof and corresponding in function in relation thereto to those of the aforesaid 70 first set and the switching means is adapted to cause electricity to be transmitted, or to interrupt such transmission of electricity, to the last mentioned rails.

A switching means may be adapted in one 75 position to interrupt the transmission of electricity to the rails to which the electro-responsive devices are connected, in another position to cause electricity for energizing the last mentioned electro-responsive devices 80 to be transmitted to the said rails, and in yet another position to permit the passage of a train over the road in question—i. e., to act as a road-making means.

In order to test the setting of any points 85 relating to a road the energization of the electromagnetic locking means is made to depend upon the correct setting of those points.

In order to guard against the simultaneous 90 making of conflicting roads, the completion by each of the road-making or switching means provided for conflicting roads of a train-clearance circuit for the corresponding road—i. e., a circuit adapted to permit a 95 train to pass along that road—is made dependent on the non-completion of a train-clearance circuit for a conflicting road by any of the said road-making or switching means.

The invention, which consists of the various features defined in the appended claims,

is illustrated by the accompanying Figs. 1, 2, and 3, which when placed side by side constitute a diagram representing an example of a set of railway tracks constructed and 5 equipped according to the invention.

Two parallel railway tracks I and II are connected together by a third track III. The roads along which it is desired to control traffic in the case of the example are 10 hereinafter called roads A, B, and C for the down journeys of trains and roads A', B', and C' for the up journeys of trains corresponding thereto respectively.

In respect of road A, which extends from 15 insulation 2 to insulation 4, what have been hereinbefore called the joining track portions are the part of the track I that extends from insulation 2 to insulation 4 and the part of track III that extends from insulation 57 to its junction with track I and the electro-responsive devices of the first set 20 are relays 27 and 59 which relate to the said two track portions respectively and the electro-responsive devices of the second set are 25 a relay 40 bridging insulation 38 in the rail portion of the track I that joins the rails on opposite sides of the track III and a relay 54 bridging insulation 47 in the rail portion of track III that joins the rails on opposite 30 sides of the track I. A relay 35 that is connected to the rails of section 60, the track portion next in advance of road A, corresponds in function to the relays 27 and 59.

In respect of road A', which extends from 35 insulation 5 to insulation 6, the joining track portions are the part of track I that extends from insulation 5 to insulation 6 and the part of track III that extends from insulation 57 to its junction with track I and the 40 electro-responsive devices of the first set are relays 35, 27, 109, 300, and 59 and the electro-responsive devices of the second set are relays 40 and 54.

In respect of road B, which extends from 45 insulation 2 to insulation 90, there are two sets of joining track portions, one of which is constituted by the joining track portions pertaining to road A and the other is constituted by the part of track II that extends 50 from insulation 90 to insulation 101 and the part of track III that extends from insulation 57 to its junction with track II and the electro-responsive devices of the first set are relays 27, 59, 103, and 88 and the electro- 55 responsive devices of the second set are the relays 40 and 54 and the relay 67 bridging insulation 65 in the rail portion of track II that joins the rails on opposite sides of track III and the relay 83 bridging insulation 80 60 in the rail portion of track III that joins the rails on opposite sides of track II. A relay 94 that is connected to the rails of section 70, the track portion next in advance of road B, corresponds in function to relays 65 27, 59, 103, and 88.

In respect of road B', which extends from insulation 92 to insulation 6, there are two sets of joining track portions, one of which is constituted by the part of track II that extends from insulation 92 to insulation 101 and the part of track III that extends from insulation 57 to its junction with track II and the other is constituted by the part of track I between insulation 6 and insulation 4 and the part of track III that extends from insulation 57 to its junction with track I and the electro-responsive devices of the first set are relays 94, 88, 103, 59, 27, 109, and 300 and the electro-responsive devices of the second set are 80 relays 67, 83, 40, and 54.

In respect of road C, which extends from insulation 101 to insulation 90, the joining track portions are the part of track II that extends from insulation 101 to insulation 90 85 and the part of track III that extends from insulation 57 to its junction with track II and the electro-responsive devices of the first set are relays 88 and 59 and the electro-responsive devices of the second set are 90 relays 67 and 83. Relay 94 that is connected to the rails of section 70, the track portion next in advance of road C, corresponds in function to the relays 88 and 59.

In respect of road C', which extends from insulation 92 to insulation 97, the joining track portions are the part of track II that extends from insulation 92 to insulation 97, and the part of track III that extends from insulation 57 to its junction with track II 100 and the electro-responsive devices of the first set are relays 94, 88, 59, 103, and 98 and the electro-responsive devices of the second set are relays 67 and 83.

For the roads A and A', the roads B and B', and the roads C and C' there are provided switch arms A, B, and C respectively. Each switch arm has one position, hereinafter referred to as the neutral position, in which it does not close any circuit for the up and down roads to which it pertains. The switch arm A when moved to the right side closes in succession circuits relating to the road A and when moved to the left closes in succession circuits relating to the road A'. Similarly, each of the switch arms B and C when moved to the right of its neutral position closes in succession circuits relating to the corresponding down road and when moved to the left of its neutral position closes in succession circuits relating to the corresponding up road. It is evident that one switch arm may be provided for each down road and another for each up road but if that be done the connections must, of course, be such that when 115 circuits be made for the down road circuits will not be made for the up road and vice versa.

The points pertaining to roads A and B and A' and B' have a points indicator SA 130

comprising a contact rod adapted to be moved by the said points, insulated contact pieces affixed to the rod, and contacts with which the contact pieces are adapted to come into contact; and the points relating to roads B and C and B' and C' have another similar points indicator SC.

It will now be explained how a signalman may test and make road A for a train which 10 may, for example, be on section 50, it being assumed or the sake of simplicity that no other train or vehicle is on the system of tracks and that the due passage of current is not interfered with by rail breakage or failure of insulation or otherwise. The signalman first moves switch arm A from its neutral position into a first position to the right of the neutral position in which its insulated contacting piece 7 makes contact with contacts 9 and 3, its insulated contacting piece 17 makes contact with contact 18, and its insulated contact 186 makes contact with contact 31, and current passes from battery 1 by way of wires 19 and 20, insulated contacting piece 7 of switch arm A, contact 9, wires 21 and 22, resistance 23, and wire 24 to the rails 25 to the right of insulation 2; thence part of the current passes by way of the rails 25 to insulation 4, then by way of wire 30 26, relay 27, wire 28, to rails 33 of section 60, thence by way of rails 33 to insulation 5, thence by way of wire 34, relay 35, wire 36, to rails 37 opposite to insulation 5, thence by way of rails 37 to insulation 38, thence 35 by way of wire 39, relay 40, wire 41, to the rails 42 on the other side of insulation 58, thence by way of rails 42 to wire 43 connected thereto opposite insulation 6, thence by way of wire 43, contact 18, insulated contacting piece 17 of switch arm A, wire 44, back to the battery by way of wire 45; part 40 of the current also passes from the rails 25 by way of points blade 46 to insulation 47, thence by way of wire 48, relay 54, wire 55, to the rails 56 on the other side of insulation 47, thence by way of rails 56 to insulation 57, thence by way of wire 58, relay 59, wire 62, to rails 63 on the other side of insulation 57 and thence along rails 63; part of the 50 current passes from the rails 63 by way of rails 148 to insulation 90, then by way of wire 87, relay 88, wire 89, to the rails 91 on the other side of insulation 90, thence by way of the rails 91, to insulation 92, wire 93, relay 94, wire 95 to the rails 86 opposite to the insulation 92, thence by way of rails 86, and rails 85 to insulation 80, wire 84, relay 83, wire 81, to rails 73 on the other side of insulation 80, thence by way of rails 73 60 to rails 42, wire 43, contact 18, insulated contacting piece 17 of switch arm A, wire 44, and back to the battery 1 by way of wire 45; another part of the current passes from rails 63 by way of rails 64 to insulation 65, thence by way of wire 66, relay 67, wire 69, rails 72, rails 73, and back to the battery 1 by way of the path hereinbefore described; a further part of the current passes from the junction of rails 86 and rails 85 along further rails 86 of section 74 (extending from insulation 65 to insulation 101), rails 86 of section 75 (extending from insulation 101 to insulation 97) to wire 96 connected to rails 86 opposite to insulation 97, thence by way of wire 96, relay 98, wire 99, to rails 100 near 75 insulation 97, thence by way of rails 100 to insulation 101, thence by way of wire 102, relay 103, wire 104, to rails 105 of section 74 near to insulation 101, thence by way of rails 105 and along said rails 73 back to the 80 battery 1 by way of the path hereinbefore described; the remainder of the current arriving at the rails 25 by way of the wire 24 passes from the rails 25 to the rails 42 by way of wire 106, relay 109, wire 110, to rails 85 317 of section 50 near insulation 2, along rails 317 to rails 42 by way of the wheels and axles of the train that is assumed to be in section 50 or, in its absence, along rails 317 to near insulation 6, then by way of 90 wire 16, relay 300, and wire 229 to rails 42. Thus all the said relays 54, 27, 35, 40, 59, 88, 94, 67, 83, 103, 98, and 109 are energized and the positions of the armatures of relays 54, 27, 40, and 59 are at this stage used for testing whether the road A, the points thereof, and the rails adjacent to the points are in order and unoccupied by a railway vehicle to ascertain whether the points relating to road A may be duly moved into the required position for that road if they are not already in the required position. The energization of the said relays 54, 27, 40, and 59 enables current to flow from insulated contacting piece 7 to contact 3, thence by way of wire 100 105 10, insulated contact 11 on switch arm B and contact 12 (which are in contact if, as is assumed, switch arm B is in its neutral position), wires 13 and 14, armature 177 of relay 27, contact 178, wire 179, insulated contact 180 on armature 149 of relay 59, contact 181, wire 182, contact 142, insulated contact 141 on armature 150 of relay 40, wire 183, armature 185 of relay 54, contact 189, wire 184, insulated contact 186 on switch 110 arm A, contact 31, wires 30 and 138, coil 155, and by way of wires 190 and 45 to battery 1. The armature 153 of the coil 155 is adapted, when the coil 155 is de-energized, to lock the switch arm A against its movement from an earlier position into a later position, but when the said coil 155 is energized, to unlock the switch arm A; the armature 153 is provided with a resilient stop 154 adapted by being ramped in one direction or arranged in cam form to prevent movement of switch arm A from an earlier position into a later position when the coil 155 is de-energized but at the same time to allow the switch arm to be moved from a later 120 115 125 130

position into an earlier position: the switch arms B and C are provided with similarly acting locking means. The insulation 57 should be put at such a distance from road 5 A that no part of any vehicle standing on any part of track III will foul track I without short-circuiting the relay 59 and a similar remark applies as regards the fouling of track II by a vehicle on track III; consequently where the length of the track III is so short that one insulation such as 57 cannot be sufficiently distant from both of the tracks I and II for the purpose in question two insulations each provided with a 10 corresponding relay should be used and adapted as indicated herein to detect whether any part of a vehicle standing on track III is fouling track I or track II. The signalman, finding switch arm A unlocked and 15 consequently knowing that all is in order for the setting of the points for road A—i. e., that the rails of the road A, the points blades, and the rails adjacent to the points are intact, that the insulations are intact, 20 and that the road A and the rails adjacent to the points are unoccupied, moves switch arm A further to the right into a second position in which its insulated contacting piece 7 makes contact with contact 160 and 25 its insulated contacting piece 17 makes contact with contact 159 and current flows from battery 1 to insulated contacting piece 7 and from insulated contacting piece 17 back to battery 1 by way of the paths hereinbefore 30 described with reference to the first position on the right of switch arm A, whilst the flow from insulated contacting piece 7 to insulated contacting piece 17 is by way of contact 160, wires 32 and 49, motor 52, wire 53, and 35 contact 159. The motor 52, being thus energized, moves the points into the required position and locks them in the known way. If the said points are in the required position the points indicator SA relating to 40 those points completes in part by corresponding contacts and connections the circuits next required for road A. The points having been moved into the correct position, the signalman moves switch arm A further 45 to the right into a third position in which its insulated contacting piece 7 makes contact with contacts 77 and 161, its insulated contacting piece 17 makes contact with contact 78 and its insulated contact 50 186 makes contact with contact 187 and current passes from battery 1 to insulated contacting piece 7 and from insulated contacting piece 17 back to battery 1 by way of the paths hereinbefore 55 described with reference to the first position on the right of switch arm A, whilst the flow from insulated contacting piece 7 to insulated contacting piece 17 is by way of contact 77, wire 165, insulated contact 60 166 of points indicator SA and contact 167 (which are in contact if, as is assumed, the 65 corresponding points are duly set in the correct position for a train to proceed along road A over those points), wires 168, 169, and 22, resistance 23, wire 24, and rails 25, thence to wire 43 as hereinbefore described 70 through inter alia the coils of the relays 40, 54, 27, 35, and 59, which are consequently energized if the respective sections are all in order, including their being unoccupied by vehicles or pairs of wheels thereof, and 75 from wire 43 by way of wire 172 and contact 78. The movement of the armatures of the last mentioned relays produced by their energization causes current to flow by way of contact 161, wire 173, insulated contact 202 80 on switch arm B and contact 203 (which are in contact if the switch arm B is in its neutral position), thence by way of wire 228, contact 174, armature 175 of energized relay 35, wires 176 and 14, armature 177 of 85 energized relay 27, contact 178, wire 179, insulated contact 180 of armature 149 of energized relay 59, contact 181, wire 182, contact 142, insulated contact 141 of armature 150 of energized relay 40, wire 183, armature 90 185 of energized relay 54, contact 189, wire 184, insulated contact 186 of switch arm A, contact 187, wire 188, coil 155, and wires 190 and 45, to battery 1. The coil 155 is thus energized and its energization causes 95 the unlocking of switch arm A in the manner hereinbefore described. The signalman finding switch arm A unlocked and consequently knowing that all is in order for making road A—i. e., for supplying clearance current to the train in section 50 to enable it to pass along road A—moves switch arm A into the fourth position on the right in which its insulated contacting piece 7 makes contact with contact 164 and its 100 insulated contacting piece 17 makes contact with contact 163 and current passes from battery 1 to insulated contacting piece 7 and from insulated contacting piece 17 back to battery 1 by way of the paths hereinbefore 105 described with reference to the first position on the right of switch arm A, whilst the flow from insulated contacting piece 7 to insulated contacting piece 17 is by way of contact 164, wire 195, contact 211 110 and insulated contact 212 of the points indicator SA (which are in contact if, as is assumed, the corresponding points are duly set in the correct position for a train to proceed along road A over those points), wire 115 213, insulated contact 216 of switch arm B and contact 217 (which are in contact if switch arm B is in its neutral position), wire 82 to rails 37 opposite to insulation 4, thence by way of rails 37 up to insulation 120 38, thence by way of wire 39, relay 40, wire 41 to rails 42, thence by way of rails 42 to wire 43 opposite to insulation 4, and thence by way of wires 43, 172, and 171, and contact 163. 125 130

The resistance of the relay 40 and in fact the resistance of all the other track relays used should be low for best results and the current or currents of electricity used for 5 testing any said track relays should be different in form, nature, direction, strength, or frequency from that supplied for the purpose of giving a train clearance; only one source of electricity—namely, battery 1—is 10 shown in the diagram and has hitherto been mentioned in connection therewith for convenience of illustration but it is to be understood that any number of sources of electricity may be used. Thus, one source of 15 electricity may be used for the purpose of testing, another for the purpose of operating the points, and another for supplying clearance electricity. Difference in strength between the current used for energizing the 20 relays in the testing operations and the current for giving a train clearance is, in the example illustrated by the diagram, produced by causing the former current to flow to the said relays by way of resistance 25 23 so that the current then flowing is sufficient for the purpose of energizing the said relays but insufficient for the purpose of giving a train clearance and by causing the latter current to flow by way of a path that 30 does not include the said resistance 23 and furthermore short-circuits certain though not all of the said relays so that the said latter current is sufficient for the purpose of giving a train clearance. For convenience 35 of illustration all the track relays have been stated to be energized when the switch arm A occupies the first and second positions on the right but with any particular position of the switch arm A only those relays need 40 be energized whose armatures are to be used for the purpose of forming part of an unlocking circuit for the switch arm. The current thus caused to pass through the rails 37 and 42 of road A and section 50 is adapted 45 to produce an indication of line clear on the train by means of suitable apparatus thereon or to prevent the production of a warning or stopping operation thereon by apparatus adapted to produce such an operation in the 50 absence of the flow therethrough of current suitable for restraining the production of such operation. It is of course to be understood that in all cases the current of electricity supplied to the train should be led 55 to the track rails at a point at the end of the road that is remote from the end of the road at which the train enters the road so that if there be a failure of a material connection the train will be automatically 60 warned or stopped. Instead of relying on apparatus on the train adapted to be influenced as just stated by current passing through the rails of the track the apparatus on the train may be adapted to produce a 65 warning or stopping operation or both only under the influence of ramps on the track and then only in the absence of a restraining current and hereinafter will be described an arrangement whereby the train current will be caused to pass through such 70 ramps instead of along the track rails so as to prevent a warning or stopping operation or warning and stopping operation from being performed on the train in contact with one of the ramps. Again instead 75 of supplying the clearance current to the train at all it may be arranged to control the placing of signals into the line clear position, signals being then relied on exclusively; or the operation of signals may thus 80 be controlled in the manner just described in addition to the supplying of current to trains for producing indications or controlling the operation of apparatus thereon.

If there is any other road to be made beyond road A it is or may be correspondingly equipped and in the case of all roads (including both down and up roads) with the exception of track terminating roads such as roads A', B', and C', a section or portion 90 in advance of the road to be made is tested in the manner hereinbefore illustrated with reference to road A to ascertain if any other train is on any part of that section or portion. 95

Any road may be made for a train in a manner corresponding to that herein indicated by the use of separate switches for effecting operations hereinbefore described as effected by one switch but in that case the 100 separate switches should each have contacts and connections whereby the making of a road by a switch or switches pertaining to a conflicting road or roads is rendered impossible in a manner such as that hereinbefore described with reference to the use of switch arm A in connection with road A, unless the switches for the road in question 105 are in their neutral position.

If clearance along a road is to be obtained by the use of track signals, the clearance current, instead of being led as aforesaid, is supplied to an operating device, as for example, an electromagnet the armature of which is adapted, on the energization of the electromagnet, to move a signal arm or allow it to move or be moved into the line-clear position. 110

In the case of the testing and the making of road A', a train being on section 61 120 (which extends to the right of section 60 from insulation 6 to insulation 192) the signalman moves switch arm A from its neutral position into a first position to the left of its neutral position in which its insulated contacting piece 7 makes contact with contacts 221 and 79, its insulated contacting piece 17 makes contact with contact 114, and its insulated contact 242 makes contact with contact 108. Current now 125 130

passes from battery 1 by wires 19 and 20 to the insulated contacting piece 7 of switch arm A, contact 221, wire 218, and wire 43 to rails 42 and thence to the rails 317 by way of the paths hereinbefore described with reference to the first position on the right of switch arm A but in the opposite direction and (as for convenience of description section 50 along with the other pertinent portions of the tracks is assumed to be unoccupied) through relay 300 in addition to all the other relays, thence by way of wire 111, contact 114, insulated contacting piece 17, and back to battery 1 by way of wires 44 and 45. The train on section 61 short-circuits a track relay (not shown) joined across the rails of section 61 but that relay is not used for the testing of road A'. If all is in order, the relays relating to the points common to tracks I and III (namely 59, 40, 54, 27, and 109) are duly energized and consequently enable current to flow from insulated contacting piece 7 to contact 79, thence by way of wire 99, insulated contact 197 on switch arm B and contact 198 (which are in contact if, as is assumed, switch arm B is in its neutral position), wire 199, contact 200, insulated contact 201 on armature 177 of relay 27, wire 204, insulated contact 205 on armature 149 of relay 59, contact 206, wires 207 and 251, contact 208, insulated contact 209 on armature 150 of relay 40, wire 210, insulated contact 214 on armature 185 of relay 54, contact 220, wire 222, contact 223, insulated contact 224 on armature 116 of relay 109, wires 252, 225, and 241, insulated contact 242 on switch arm A, contact 108, wires 107, 234, and 138, coil 155, and back to battery 1 by way of wires 190 and 45. The energization of coil 155 causes the unlocking of switch arm A and the signalman, finding switch arm A unlocked and consequently knowing that all is in order for the setting of the points for road A', moves switch arm A further to the left into a second position in which its insulated contacting piece 7 makes contact with contact 226 and its insulated contacting piece 17 makes contact with contact 115 and current passes from battery 1 to insulated contacting piece 7 and from insulated contacting piece 17 back to battery 1 by way of the paths hereinbefore described, whilst the flow from insulated contacting piece 7 to insulated contacting piece 17 is by way of contact 226, wires 112 and 49, motor 52, wires 53 and 227, and contact 115. The motor 52, being thus energized, moves the points and locks them therein in the known way. The signalman then moves switch arm A further to the left into a third position in which its insulated contacting piece 7 makes contact with contacts 122 and 230, its insulated contacting piece 17 makes contact with contact 123, and its insulated contact 242 makes contact with contact 233, and current passes from battery 1 to insulated contacting piece 7 and from insulated contacting piece 17 to battery 1 along the paths hereinbefore described, whilst the flow from insulated contacting piece 7 to insulated contacting piece 17 is by way of contact 122, wire 231, contact 235 and insulated contact 215 of points indicator SA (which are in contact if the points connecting tracks I and III are set in the correct position), wires 237 and 43, to rails 42, and thence to wire 111 by way of the relay-energizing path described with reference to the first position on the left of switch arm A through inter alia the coils of the relays 35, 27, 59, 40, 54, and 109, then by way of wires 111 and 113 and contact 123. The movement of the armatures of the last mentioned relays produced by their energization causes current to flow by way of contact 230, wires 232 and 262, contact 301 and insulated contact 302 of switch arm B (which are in contact if switch arm B is in its neutral position), wires 253 and 228, contact 174, armature 175 of relay 35, wires 176 and 14, armature 177 of relay 27, contact 178, wire 179, insulated contact 180 of armature 149 of relay 59, contact 181, wire 182, contact 142, insulated contact 141 of armature 150 of relay 40, wire 183, armature 185 of relay 54, contact 119, wire 118, contact 117, armature 116 of relay 109, wire 157, armature 158 of relay 300, contact 295, wire 241, insulated contact 242 of switch arm A, contact 233, wires 234 and 138, coil 155, and wires 190 and 45, to battery 1. The energization of coil 155 causes the unlocking of switch arm A and the signalman finding switch arm A unlocked and consequently knowing that all is in order for supplying clearance current to the train on section 61 to enable it to pass along road A', moves switch arm A still further to the left into a fourth position so as to bring its insulated contacting piece 7 into contact with contact 243, and its insulated contacting piece 17 into contact with contact 245 and current passes from battery 1 to insulated contacting piece 7 and from insulated contacting piece 17 back to battery 1 by way of the paths hereinbefore described with reference to the last two preceding operations of switch arm A, whilst the flow from insulated contacting piece 7 to insulated contacting piece 17 is by way of contact 243, wires 219, 218, and 43, rails 42, to insulation 38, wire 41, relay 40, wire 39, rails 149, rails 37, wire 247, contact 248 of points indicator SA and contact 249 (which are in contact if the points connecting tracks I and III are in the correct position), wire 250, insulated contact 151 of switch arm B

and contact 303 (which are in contact if switch arm B is in its neutral position), wires 304 and 262, and contact 245. Current or electricity is thus supplied to the 5 train on section 61 and will continue to be supplied to the train right up to its arrival at the end of road A'.

It will now be explained how a signalman tests and makes road B for a train on 10 for example section 50, it being assumed, as in the case of road A, that no other train or vehicle is on the system of tracks and that the due passage of current is not interfered with by rail breakage or failure of 15 insulation or otherwise. The signalman moves switch arm B from its neutral position to a first position to the right of the neutral position in which its insulated contacting piece 306 makes contact with contacts 307 and 125, its insulated contacting piece 313 makes contact with contact 312, its insulated contact 20 121 makes contact with contact 139, and current passes from battery 1 by way of wires 19 and 305, insulated contacting piece 25 306 of switch arm B, contact 307, wires 308 and 169, to wire 22, thence by the paths previously traced in connection with road A through relays 54, 27, 35, 40, 59, 88, 94, 67, 83, 103, 98, and 109, to wire 30 43, and thence by way of wires 43, 309, 310, and 311, contact 312, insulated contacting piece 313 on switch arm B, wire 314, and back to battery 1 by way of wires 44 and 45. Thus all the last mentioned relays are 35 energized and the positions of the armatures of relays 27, 40, 54, 59, 67, 83, 88, and 103 are at this stage used for testing whether the road B, the points thereof, and the rails adjacent to the points are in order and unoccupied by a railway vehicle to ascertain 40 whether these points may be duly moved into the required positions for that road if they are not already in the required positions. The energization of the said relays 45 27, 40, 54, 59, 67, 83, 88, and 103 enables current to flow from insulated contacting piece 306 to contact 125, thence by way of wire 127, insulated contact 128 on switch arm A and contact 129 (which are in contact if, as is assumed, switch arm A is in its neutral position), wire 130, insulated contact 131 on switch arm C and contact 132 (which are in contact if, as is assumed, switch arm C is in its neutral position), 50 wires 133 and 136, armature 356 of relay 88, contact 357, wire 358, armature 359 of relay 67, contact 360, wire 361, contact 362, armature 363 of relay 83, wire 364, armature 365 or relay 103, contact 366, wire 55 367, insulated contact 368 on armature 150 of relay 40, contact 369, wire 370, insulated contact 371 on armature 149 of relay 59, contact 372, wire 373, insulated contact 374 on armature 177 of relay 27, contact 375, 60 wire 376, insulated contact 377 on armature 65 185 of relay 54, contact 378, wires 379 and 265, coil 380, wires 381, 341, and 137, contact 139, insulated contact 121 on switch arm B, wires 348, 349, and 314, and thence back to the battery by way of wires 44 and 45. The 70 function of the coil 380 is similar to that of the coil 155 hereinbefore described with reference to the testing and making of roads A and A' and consequently its energization causes the unlocking of switch arm B, and 75 the signalman, finding switch arm B unlocked and consequently knowing that all is in order for setting the points, moves switch arm B further to the right into a second position in which its insulated contacting piece 80 306 makes contact with contact 315 and its insulated contacting piece 313 makes contact with contact 326 and current flows from battery 1 to insulated contacting piece 306 and from insulated contacting piece 313 85 back to battery 1 by way of the paths hereinbefore described, whilst the flow from insulated contacting piece 306 to insulated contacting piece 313 is by way of contact 315, wires 140 and 143, motor 52, wire 144, motor 90 145, wire 146, and contact 326. The motors 52 and 145, being thus energized, move the points connecting tracks I and III and the points connecting tracks II and III into 95 the positions required for making road B and lock them therein in the known way. The signalman then moves switch arm B further to the right into a third position in which its insulated contacting piece 306 makes contact with contacts 147 and 327, 100 its insulated contacting piece 313 makes contact with contact 152, and its insulated contact 121 makes contact with contact 124, and current passes from battery 1 to insulated contacting piece 306 and from insulated contacting piece 313 back to battery 1 105 by way of the paths hereinbefore described, whilst the flow from insulated contacting piece 306 to insulated contacting piece 313 is by way of contact 147, wire 318, insulated contact 319 on points indicator SA and contact 320 (which are in contact if the points connecting tracks I and III are home in the correct position), wire 321, insulated contact 322 on points indicator SC 110 and contact 323 (which are in contact if the points connecting tracks II and III are home in the correct position), wire 324, wire 169 to wire 22, and thence by the paths previously traced in connection with the first 115 position to the right of switch arm B through relays 54, 27, 35, 40, 59, 88, 94, 67, 83, 103, 98, and 109 to wire 311, and thence by way of wires 311 and 325 and contact 152. The movement of the armatures of 120 relays 94, 88, 67, 83, 103, 40, 59, 27, and 54 produced by their energization causes current to flow by way of contact 327, thence by way of wire 328, insulated contact 329 on switch arm A and contact 330 (which are 125 130.

in contact if as is assumed switch arm A is in its neutral position), wire 331, contact 332 and insulated contact 333 on switch arm C (which are in contact if as is assumed 5 switch arm C is in its neutral position), wire 334, armature 353 of energized relay 94, contact 354, wires 355 and 136, armature 356 of energized relays 88, contact 357, wire 358, armature 359 of energized relay 67, 10 contact 360, wire 361, contact 362, armature 363 of energized relay 83, wire 364, armature 365 of energized relay 103, contact 366, wire 367, insulated contact 368 on armature 150 of energized relay 40, contact 15 369, wire 370, insulated contact 371 on armature 149 of energized relay 59, contact 372, wire 373, insulated contact 374 on armature 177 of energized relay 27, contact 375, wire 376, insulated contact 377 on armature 20 185 of energized relay 54, contact 378, wires 379 and 265, coil 380, wires 381 and 341, contact 124, insulated contact 121 of switch arm B, wires 348 and 349, to wire 314, and thence back to battery 1 by way of wires 44 25 and 45. The coil 380 is thus energized and its energization causes the unlocking of switch arm B in the manner hereinbefore described. The signalman finding switch arm B unlocked and consequently knowing 30 that all is in order for supplying clearance current to the train on section 50 to enable it to pass along road B, moves switch arm B still further to the right into a fourth position, in which its insulated contacting piece 306 makes contact with contact 382 and its insulated contacting piece 313 makes contact with contact 383 so that current passes from battery 1 to insulated contacting piece 306 and from insulated contacting piece 313 back to battery 1 by way of the paths hereinbefore described with reference to the first position on the right of switch arm B, whilst the flow from insulated contacting piece 306 to insulated contacting 35 piece 313 is by way of contact 382, wire 384, insulated contact 385 on switch arm A and contact 386 (in contact only when switch arm A is in its neutral position), wire 387, insulated contact 388 on switch arm C and contact 389 (in contact only when switch arm C is in its neutral position), wire 390, contact 391 and insulated contact 392 on points indicator SA (which are in contact if as is assumed the corresponding points 40 are in the correct position for a train to pass thereover from track I to track III), wire 393, insulated contact 394 on points indicator SC and contact 395 (which are in contact if as is assumed the corresponding points are in the correct position for a train to pass thereover from track III to track II), wire 396 to the rails 86 opposite to insulation 90, thence along rails 86 and points blade 85, to near insulation 80, 45 thence by way of wire 84, relay 83, and wire

81 to the rails 73 on the other side of insulation 80, thence by way of rails 73 and 42 to wire 43 opposite to insulation 6, and thence by way of wires 43, 309, 310, 311, 325, and 316 and contact 383. The current 70 now passing by way of rails 86, points blade 85, and rails 73 and 42 enables a train equipped with apparatus such as hereinbefore described to pass on and along road B.

In the case of the testing and the making 75 of road B', a train being supposed to be on section 71, the signalman moves switch arm B from its neutral position into a first position to the left of its neutral position in which its insulated contacting piece 306 80 makes contact with contacts 397 and 156, its insulated contacting piece 313 makes contact with contact 398, and its insulated contact 429 makes contact with contact 120. Current now passes from battery 1 by way 85 of wires 19 and 305, insulated contacting piece 306 on switch arm B, contact 397, and wires 399, 311, 310, 309, and 43 to rails 42 and thence to the wire 308 by way of the paths hereinbefore described with 90 reference to the first position to the right of switch arm B but in the opposite direction and (as for convenience of description section 50 along with the other pertinent portions of the tracks is assumed to 95 be unoccupied) through relay 300 in addition to all the other relays, thence by way of wires 308 and 400, and contact 398 to insulated contacting piece 313, and back to battery 1 by way of the path hereinbefore 100 described. If all is in order for setting the points, the relays 27, 40, 54, 59, 67, 83, 88, 103, and 109 are duly energized and consequently enable current to flow from insulated contacting piece 306 to contact 156, thence 105 by way of wire 162, insulated contact 254 on switch arm A and contact 255 (which are in contact if, as is assumed, switch arm A is in its neutral position), wire 256, insulated contact 257 on switch arm C and contact 258 (which are in contact if, as is assumed, switch arm C is in its neutral position), wire 259, insulated contact 260 on armature 356 of energized relay 88, contact 261, wire 263, insulated contact 227 on armature 359 of energized relay 67, contact 236, wire 238, contact 239, insulated contact 240 on armature 363 of energized relay 83, wire 246, insulated contact 267 on armature 365 of energized relay 103, contact 268, wires 110 269 and 251 contact 208, insulated contact 209 on armature 150 of energized relay 40, wire 210, insulated contact 214 on armature 195 of energized relay 54, contact 220, wire 222, contact 223, insulated contact 224 on 115 armature 116 of energized relay 109, wires 252, 270, and 265, coil 380, wires 381, 183, and 170, contact 188, insulated contact 429 on switch arm B, and back to battery 1 by 120 way of wires 433, 349, 314, 44, and 45. The 130

energization of coil 380 causes the unlocking of switch arm B and the signalman, finding switch arm B unlocked and consequently knowing that all is in order for the setting 5 of the points for road B', moves switch arm B further to the left into a second position in which its insulated contacting piece 306 makes contact with contact 401 and its insulated contacting piece 313 makes contact 10 with contact 402 and current passes from battery 1 to insulated contacting piece 306 and from insulated contacting piece 313 back to battery 1 by way of the paths hereinbefore described, whilst the flow from insulated contacting piece 306 to insulated contacting piece 313 is by way of contact 401, wires 191 and 143, motor 52, wire 144, motor 145, wires 146 and 193, and contact 402. The motors 52 and 145, being thus energized, 15 move the points connecting tracks I and III and the points connecting tracks II and III into the positions required for making road B' and lock them therein in the known way. The signalman then moves 20 switch arm B further to the left into a third position so that its insulated contacting piece 306 makes contact with contacts 194 and 411, its insulated contacting piece 313 makes contact with contact 196, and its insulated contact 25 contact 429 makes contact with contact 120; current consequently flows from battery 1 to insulated contacting piece 306 of switch arm B and from insulated contacting piece 313 to battery 1 along the paths hereinbefore described, whilst the flow from insulated contacting piece 306 to insulated contacting piece 313 is by way of contact 194, wire 403, contact 404 and insulated contact 405 of points indicator SA (which are in contact 30 if the points connecting tracks I and III are home in the correct position), wire 406, insulated contact 407 on points indicator SC and contact 408 (which are in contact if the points connecting tracks II and III 35 are home in the correct position), and wire 409 to wire 310, and thence to wire 308 by way of the path hereinbefore described with reference to the first position on the left of switch arm B through inter alia the coils 40 of the relays 109, 300, 94, 88, 67, 83, 103, 40, 59, 27 and 54, then by way of wires 308 and 410 and contact 402. The movement of the armatures of the last mentioned relays produced by their energization causes current 45 to flow by way of contact 411, wire 412, contact 413 and insulated contact 414 on switch arm C (which are in contact if as is assumed switch arm C is in its neutral position), wire 415, contact 416 and insulated contact 417 on switch arm A (which are in contact if as is assumed switch arm A is in its neutral position), wire 418, contact 437, insulated contact 438 on armature 116 of energized relay 109, wire 439, insulated contact 440 on armature 158 of energized relay 50 300, contact 441, wire 442 to armature 353 of relay 94, thence to the coil 380 by way of the armature path hereinbefore described with reference to the corresponding position occupied by switch arm B when testing road 70 B, and after passing through the coil 380 the current passes by way of wires 381 and 183, contact 120, insulated contact 429, wires 438 and 349 back to battery 1 by way of wires 314, 44, and 45. The energization of coil 75 380 causes the unlocking of switch arm B, and the signalman, finding switch arm B unlocked and consequently knowing that all is in order for supplying clearance current to the train on section 71 to enable it to pass 80 along road B', moves switch arm B still further to the left into a fourth position so as to bring its insulated contacting piece 306 into contact with contact 444 and its insulated contacting piece 313 into contact 85 with contact 445, and current consequently passes from battery 1 to insulated contacting piece 306 and from insulated contacting piece 313 back to battery 1 by way of the paths hereinbefore described with reference 90 to the last two preceding operations of switch arm B, whilst the flow from insulated contacting piece 306 to insulated contacting piece 313 is by way of contact 444, wire 446, contact 447 and insulated contact 448 on points indicator SA (which are in contact if the points connecting tracks I and III are home in the correct position), wire 449, insulated contact 450 on points indicator SC and contact 451 (which are in contact if the 95 points connecting tracks II and III are home in the correct position), wire 452, insulated contact 453 on switch arm C and contact 454 (which are in contact if as is assumed switch arm C is in its neutral position), wire 455, insulated contact 456 on switch arm A and contact 457 (which are in contact if as is assumed switch arm A is in its neutral position), and wires 458, 309, 43, to rails 42, thence to rails 86 by way 100 of the path hereinbefore described with reference to the corresponding position occupied by switch arm B when making road B but in the opposite direction, along rails 86 to wire 266, and thence by way of wire 105 266 and contact 445. Current or electricity is thus supplied to the train on section 71 and will continue to be supplied to the train right up to its arrival at the end of the road B'. 110

The connections and operations for the testing and the making of roads C and C' are similar to those hereinbefore described for the testing and making of roads A and A' but for the sake of clearness not all the 115 connections pertaining to roads C and C' are shown.

For the purpose of illustrating the employment of ramps in apparatus according to the invention two ramps—namely, a warn- 120

125

130

ing ramp 290 and a stopping ramp 291—are shown in section 61. The stopping ramp is adapted to give a contacting device on a train, on interacting therewith, a displacement that differs from the displacement which the warning ramp is adapted to give the said contacting device. In this way the warning ramp is adapted in the absence of electrical restraint to cause the production 10 of a warning operation on a train and the stopping ramp is adapted in the absence of electrical restraint to cause the production of a stopping operation on a train. The ramps 290 and 291 relate to road A' and 15 have common to them a wire 292 which is connected by a wire 293 with contact 244 of switch A so that after road A' has been tested and when switch arm A is moved to occupy the fourth position to the left of its 20 neutral position the said restraining electricity or clearance current passes from battery 1, by way of wires 19 and 20, insulated contacting piece 7 of switch arm A, contact 244, wire 293, ramp 290 or ramp 291 (which 25 ever be in contact with the contacting device of the train), the said contacting device, means on the train for restraining a warning and (or) stopping operation, wheels of the locomotive, rails 37, wire 247, the path 30 through the points indicator contacts and the contacts of switch arm B previously traced for the train-clearance current for road A, contact 245, insulated contacting piece 17 of switch arm A, and wires 44 and 35 45 to battery 1.

Instead of employing rails of the track for the clearance current as hereinbefore described there may be used similarly a conductor running parallel with the rails.

40 The length of a track portion or section the condition of which is adapted to be indicated by a track relay provided therefor is determined by the conditions of track ballast or other circumstances and may in 45 some cases be only a few feet. The track relays of different track portions or sections may obviously be adapted to be energized by different sources of electricity instead of by one as shown in the diagram.

50 The track apparatus may be adapted to supply for the clearance of trains along a given portion of track currents or electricity differing (as in direction or frequency) for the two directions of travel of the trains and 55 the apparatus on the trains may be adapted to give clearance for the two directions only when receiving current or electricity appropriate (as in direction or frequency) to the direction of travel.

60 When a train has passed out of the required road the signalman should place the switch arm pertaining to that road in its neutral position in order that its contacts may, as hereinbefore indicated, close in part 65 circuits required for the testing and making

of some other road. Any train-clearance circuit may if desired be formed in part by contacts pertaining to any suitable track or other relay or device (for example a signal).

What I claim is:—

70

1. Track apparatus for the electrical control of trains on joining track portions comprising a source or sources of electricity, traffic-controlling electro-responsive devices constituting a first set connected to rails of 75 the track portions respectively and adapted to be energized by electricity from said source or one or more of said sources and to be de-energized when disconnected from such energizing source or sources or when short- 80 circuited therefrom, as by conductively connected wheels of a railway vehicle, an insulation located in each rail portion joining opposite sides of a track portion, and a traffic-controlling electro-responsive device of a 85 second set bridging each said insulation and adapted to be de-energized on the failure of the corresponding insulation, substantially as described.

2. Apparatus according to claim 1 comprising, for the making by a signalman of a road including one of said track portions, manual road-making means, electromagnetic locking means adapted unless energized to prevent said road-making means from being 90 so operated as to permit the passage of a train over said road, and means adapted to cause said electromagnetic locking means to be energized only when all said electro-responsive devices are energized, substantially 100 as described.

3. Track apparatus for the electrical control of trains on joining track portions comprising a source or sources of electricity, traffic-controlling electro-responsive devices 105 constituting a first set connected to rails of the track portions respectively and adapted to be energized by electricity from said source or one or more of said sources and to be de-energized when disconnected from such energizing source or sources or when short-circuited therefrom, as by conductively connected wheels of a railway vehicle, an insulation located in such rail portion joining opposite sides of a track portion, a 115 traffic-controlling electro-responsive device of a second set bridging each said insulation and adapted to be de-energized on the failure of the corresponding insulation, manual road-making means for the making of a road 120 including one of said track portions by a signalman, a traffic-controlling electro-responsive device connected to rails of a track portion immediately in front of said road and adapted to be energized by electricity 125 from said source or one or more of said sources and to be de-energized when disconnected from such energizing source or sources or when short-circuited therefrom,

as by conductively connected wheels of a 130

- railway vehicle, electromagnetic locking means adapted unless energized to prevent said road-making means from being so operated as to permit the passage of a train over said road, and means adapted to cause said electromagnetic locking means to be energized only when all said electro-responsive devices are energized, substantially as described.
- 5 4. Track apparatus for the electrical control of trains on joining track portions comprising a source or sources of electricity, traffic-controlling electro-responsive devices constituting a first set connected to rails of the track portions respectively and adapted to be energized by electricity from said source or one or more of said sources and to be de-energized when disconnected from such energizing source or sources or when 15 short-circuited therefrom, as by conductively connected wheels of a railway vehicle, an insulation located in each rail portion joining opposite sides of a track portion, a traffic-controlling electro-responsive device of a second set bridging each said insulation and adapted to be de-energized on the failure of the corresponding insulation, for testing and making a road including one of said track portions switching means adapted for use by a signalman and in one position to disconnect said energizing source or sources 20 from said electro-responsive devices so as to de-energize said devices, in another position to connect said energizing source or sources with said electro-responsive devices so as to energize said devices, and in yet another position to permit the passage of a train over the road to which said switching means pertains, electromagnetic locking means adapted unless energized to prevent 25 said switching means from being moved into the last mentioned position, and means adapted to cause said electromagnetic locking means to be energized only when all said electro-responsive devices are energized, substantially as described.
- 30 5. Track apparatus for the electrical control of trains on joining track portions comprising a source or sources of electricity, traffic-controlling electro-responsive devices constituting a first set connected to rails of the track portions respectively and adapted to be energized by electricity from said source or one or more of said sources and to be de-energized when disconnected from such energizing source or sources or when 35 short-circuited therefrom, as by conductively connected wheels of a railway vehicle, an insulation located in each rail portion joining opposite sides of a track portion, a traffic-controlling electro-responsive device of a second set bridging each said insulation and adapted to be de-energized on the failure of the corresponding insulation, and, for testing a road including one of said track portions, switching means adapted for use 40 by a signalman and to connect and disconnect said energizing source or sources and said electro-responsive devices so as to energize and de-energize said devices, substantially as described.
- 45 5. Track apparatus for the electrical control of trains on joining track portions comprising a source or sources of electricity, traffic-controlling electro-responsive devices constituting a first set connected to rails of the track portions respectively and adapted to be energized by electricity from said source or one or more of said sources and to be de-energized when disconnected from such 50 short-circuited therefrom, as by conductively connected wheels of a railway vehicle, an insulation located in each rail portion joining opposite sides of a track portion, a traffic-controlling electro-responsive device connected to rails of a track portion immediately in front of a road including one of said track portions and adapted to be energized by electricity from said source or one or more of said sources and to be de-energized when disconnected from such energizing 55 source or sources or when short-circuited therefrom, as by conductively connected wheels of a railway vehicle, and, for said road, switching means adapted for use by a signalman and to connect and disconnect 60 said energizing source or sources and said 65
- electro-responsive devices so as to energize and de-energize said devices, substantially as described.
6. Track apparatus for the electrical control of trains on joining track portions comprising a source or sources of electricity, traffic-controlling electro-responsive devices constituting a first set connected to rails of the track portions respectively and adapted to be energized by electricity from said source or one or more of said sources and to be de-energized when disconnected from such energizing source or sources or when short-circuited therefrom, as by conductively connected wheels of a railway vehicle, an insulation located in each rail portion joining opposite sides of a track portion, a traffic-controlling electro-responsive device of a second set bridging each said insulation and adapted to be de-energized on the failure of the corresponding insulation, for testing and making a road including one of said track portions switching means adapted for use by a signalman and in one position to disconnect said energizing source or sources from said electro-responsive devices so as to de-energize said devices, in another position to connect said energizing source or sources with said electro-responsive devices so as to energize said devices, and in yet another position to permit the passage of a train over the road to which said switching means pertains, electromagnetic locking means adapted unless energized to prevent said switching means from being moved into the last mentioned position, and means adapted to cause said electromagnetic locking means to be energized only when all said electro-responsive devices are energized, substantially as described.
7. Track apparatus for the electrical control of trains on joining track portions comprising a source or sources of electricity, traffic-controlling electro-responsive devices constituting a first set connected to rails of the track portions respectively and adapted to be energized by electricity from said source or one or more of said sources and to be de-energized when disconnected from such energizing source or sources or when short-circuited therefrom, as by conductively connected wheels of a railway vehicle, an insulation located in each rail portion joining opposite sides of a track portion, a traffic-controlling electro-responsive device of a second set bridging each said insulation and adapted to be de-energized on the failure of the corresponding insulation, a traffic-controlling electro-responsive device connected to rails of a track portion immediately in front of a road including one of said track portions and adapted to be energized by electricity from said source or one or more of said sources and to be de-energized when disconnected from such energizing source or sources or when short-circuited therefrom, as by conductively connected wheels of a railway vehicle, and, for said road, switching means adapted for use by a signalman and to connect and disconnect said energizing source or sources and said

sources or when short-circuited therefrom, as by conductively connected wheels of a railway vehicle, and, for testing and making said road, switching means adapted for use 5 by a signalman and in one position to disconnect said energizing source or sources from said electro-responsive devices so as to de-energize said devices, in another position to connect said energizing source or sources 10 with said electro-responsive devices so as to energize said devices, and in yet another position to permit the passage of a train over the road to which said switching means pertains, electromagnetic locking means adapted 15 ed unless energized to prevent said switching means from being moved into the last mentioned position, and means adapted to cause said electromagnetic locking means to be energized only when all said electro-responsive 20 devices are energized, substantially as described.

8. Track apparatus for the electrical control of trains on track portions joined together by points comprising a source or 25 sources of electricity, traffic-controlling electro-responsive devices constituting a first set connected to rails of the track portions respectively and adapted to be energized by 30 electricity from said source or one or more of said sources and to be de-energized when disconnected from such energizing source or sources or when short-circuited therefrom, as by conductively connected wheels of a railway vehicle, an insulation located in each 35 rail portion joining opposite sides of a track portion, a traffic-controlling electro-responsive device of a second set bridging each said insulation and adapted to be de-energized on the failure of the corresponding insulation, manual road-making means for 40 the making by a signalman of a road including one of said track portions, electromagnetic locking means adapted unless energized to prevent said road-making means 45 from being so operated as to permit the passage of a train over the said road, and means adapted to cause said electromagnetic locking means to be energized only when said points are properly set for 50 said road and all said electro-responsive devices are energized, substantially as described.

9. Track apparatus for the electrical control of trains on track portions joined together by points comprising a source or 55 sources of electricity, traffic-controlling electro-responsive devices constituting a first set connected to rails of the track portions respectively and adapted to be energized by 60 electricity from said source or one or more of said sources and to be de-energized when disconnected from such energizing source or sources or when short-circuited therefrom, as by conductively connected wheels 65 of a railway vehicle, an insulation located

in each rail portion joining opposite sides of a track portion, a traffic-controlling electro-responsive device of a second set bridging each said insulation and adapted to be de-energized on the failure of the corresponding 70 insulation, manual road-making means for the making by a signalman of a road including one of said track portions, a traffic-controlling electro-responsive device connected to rails of a track portion immediately in front of said road and adapted to be energized by electricity from said source or one or more of said sources and to be de-energized when disconnected from such energizing source or sources or when 75 short-circuited therefrom, as by conductively connected wheels of a railway vehicle, electro-magnetic locking means adapted unless energized to prevent said road-making means from being so operated as to permit the passage of a train over the said road, and means adapted to cause said electromagnetic locking means to be energized only when said points are properly set for 80 said road and all said electro-responsive devices are energized, substantially as described.

10. Track apparatus for the electrical control of trains on track portions joined together by points comprising a source or 90 sources of electricity, traffic-controlling electro-responsive devices constituting a first set connected to rails of the track portions respectively and adapted to be energized by 95 electricity from said source or one or more of said sources and to be de-energized when disconnected from such energizing source or sources or when short-circuited therefrom, as by conductively connected wheels of a railway vehicle, an insulation located in each 100 rail portion joining opposite sides of a track portion, a traffic-controlling electro-responsive device of a second set bridging each said insulation and adapted to be de-energized on the failure of the corresponding insulation, for testing a road including one of 105 said track portions switching means adapted for use by a signalman and to make in part and to break the connection between said energizing source or sources and said electro-responsive devices, and circuit-closing and opening means adapted to be moved by the points pertaining to said road and only when said points are properly set for 110 said road to co-operate with said switching means in completing said connection, substantially as described.

11. Track apparatus for the electrical control of trains on track portions joined together by points comprising a source or 125 sources of electricity, traffic-controlling electro-responsive devices constituting a first set connected to rails of the track portions respectively and adapted to be energized by 130 electricity from said source or one or more

of said sources and to be de-energized when disconnected from such energizing source or sources or when short-circuited therefrom, as by conductively connected wheels of a 5 railway vehicle, an insulation located in each rail portion joining opposite sides of a track portion, a traffic-controlling electro-responsive device of a second set bridging each said insulation and adapted to be de- 10 energized on the failure of the corresponding insulation, a traffic-controlling electro-responsive device connected to rails of a track portion immediately in front of a road including one of said track portions 15 and adapted to be energized by electricity from said source or one or more of said sources and to be de-energized when disconnected from such energizing source or sources or when short-circuited therefrom, 20 as by conductively connected wheels of a railway vehicle, and for testing said road switching means adapted for use by a signalman and to make in part and to break the connection between said energizing source 25 or sources and said electro-responsive devices, and circuit-closing and opening means adapted to be moved by the points pertaining to said road and only when said points are properly set for said road to co-operate 30 with said switching means in completing said connection, substantially as described.

12. Track apparatus for the electrical control of trains on track portions joined together by points comprising a source or 35 sources of electricity, traffic-controlling electro-responsive devices constituting a first set connected to rails of the track portions respectively and adapted to be energized by electricity from said source or one or more 40 of said sources and to be de-energized when disconnected from such energizing source or sources or when short-circuited therefrom, as by conductively connected wheels of a railway vehicle, an insulation located in each 45 rail portion joining opposite sides of a track portion, a traffic-controlling electro-responsive device of a second set bridging each said insulation and adapted to be de-energized on the failure of the corresponding insulation, 50 for testing and making a road including one of said track portions switching means adapted for use by a signalman and in one position to disconnect said energizing source or sources from said electro-responsive devices so as to de-energize said devices, in another position to connect said energizing source or sources with said electro-responsive devices so as to energize them, and in yet another position to permit the passage 55 of a train over the road to which said switching means pertains, electromagnetic locking means adapted unless energized to prevent said switching means from being moved into the last mentioned position, and all said electro-responsive devices are energized, 60 substantially as described.

locking means to be energized only when said points are properly set for said road and all said electro-responsive devices are energized, substantially as described.

13. Track apparatus for the electrical control of trains on track portions joined together by points comprising a source or sources of electricity, traffic-controlling electro-responsive devices constituting a first set connected to rails of the track portions 70 respectively and adapted to be energized by electricity from said source or one or more of said sources and to be de-energized when disconnected from such energizing source or sources or when short-circuited therefrom, 75 as by conductively connected wheels of a railway vehicle, an insulation located in each rail portion joining opposite sides of a track portion, a traffic-controlling electro-responsive device of a second set bridging each said insulation and adapted to be de-energized 80 on the failure of the corresponding insulation, a traffic-controlling electro-responsive device connected to rails of a track portion immediately in front of a road including one 85 of said track portions and adapted to be energized by electricity from said source or one or more of said sources and to be de-energized when disconnected from such energizing source or sources or when short-circuited 90 therefrom, as by conductively connected wheels of a railway vehicle, and for testing and making said road switching means adapted for use by a signalman and in one position to disconnect said energizing source 95 or sources from said electro-responsive devices so as to de-energize said devices, in another position to connect said energizing source or sources with said electro-responsive devices so as to energize them, and in yet another position to permit the passage of a train over the road to which said switching means pertains, electromagnetic locking means adapted unless energized to prevent said switching means from being moved into the last mentioned position, and means adapted to cause said electromagnetic locking means to be energized only when said points are properly set for said road and all said electro-responsive devices are energized, 110 substantially as described.

14. Track apparatus for the electrical control of trains on joining track portions comprising a source or sources of electricity, traffic-controlling electro-responsive devices 115 constituting a first set connected to rails of the track portions respectively and adapted to be energized by electricity from said source or one or more of said sources and to be de-energized when disconnected from such energizing source or sources or when short-circuited therefrom, as by conductively connected wheels of a railway vehicle, an insulation located in each rail portion joining opposite sides of a track portion, a traffic- 120

130

- controlling electro-responsive device of a second set bridging each said insulation and adapted to be de-energized on the failure of the corresponding insulation, and manual 5 road-making means for conflicting roads each of which includes one of said track portions, the road-making means for each of said roads being adapted when in a position for completing a train clearance circuit for the corresponding road to prevent the completion by the road-making means for any other of said roads of a train clearance circuit therefor, substantially as described. 10
- 15 15. Track apparatus for the electrical control of trains on joining track portions comprising a source or sources of electricity, traffic-controlling electro-responsive devices constituting a first set connected to rails of the track portions respectively and adapted to be energized by electricity from said source or one or more of said sources and to be de-energized when disconnected from such energizing source or sources or when short-circuited therefrom, as by conductively connected wheels of a railway vehicle, an insulation located in each rail portion joining opposite sides of a track portion, a traffic-controlling electro-responsive device 20 of a second set of bridging each said insulation and adapted to be de-energized on the failure of the corresponding insulation, manual road-making devices for conflicting roads each of which includes one of said track portions, an electromagnetic locking means pertaining to each of said road-making devices and adapted unless energized to prevent the road-making device to which it pertains from being so operated as to permit the passage of a train over the corresponding road, and means adapted to cause each said electromagnetic locking means to be energized only when the road-making device or devices to which it does not pertain is 30 or are not making the corresponding road or roads, substantially as described. 35
16. Track apparatus for the electrical control of trains on track portions joined together by points comprising a source or sources of electricity, traffic-controlling electro-responsive devices constituting a first set connected to rails of the track portions respectively and adapted to be energized by electricity from said source or one or more of said sources and to be de-energized when disconnected from such energizing source or sources or when short-circuited therefrom, as by conductively connected wheels of a railway vehicle, an insulation located in each rail portion joining opposite sides of a track portion, a traffic-controlling electro-responsive device of a second set bridging each said insulation and adapted to be de-energized on the failure of the corresponding insulation, electromagnetic points-moving means adapted when energized to move said points so as to make for a train a road including one of said track portions, for testing said road and making said road switching means adapted for use by a signalman and in one position to disconnect said energizing source or sources from said electro-responsive devices so as to de-energize said devices, in another position to connect said energizing source or sources with said electro-responsive devices so as to energize said devices, and in yet another position to connect said electromagnetic points-moving means with said source or one or more of said sources and thus to energize said electromagnetic points-moving means, electromagnetic locking means adapted unless energized to prevent said switching means from being moved into the last mentioned position, and means adapted to cause said electromagnetic locking means to be energized only when all said electro-responsive devices are energized, substantially as described. 45
17. Track apparatus for the electrical control of trains on joining track portions comprising a source or sources of electricity, traffic-controlling electro-responsive devices constituting a first set connected to rails of the track portions respectively and adapted to be energized by electricity from said source or one or more of said sources and to be de-energized when disconnected from such energizing source or sources or when short-circuited therefrom, as by conductively connected wheels of a railway vehicle, an insulation located in each rail portion joining opposite sides of a track portion, a traffic-controlling electro-responsive device of a second set bridging each said insulation and adapted to be de-energized on the failure of the corresponding insulation, and, for testing both an "up" road and a "down" road including one of said track portions, switching means common to said "up" and "down" roads and adapted for use by a signalman and to connect and disconnect said energizing source or sources and the pertinent electro-responsive devices so as to energize and de-energize them, substantially as described. 50
18. Apparatus according to claim 1 comprising for the making by a signalman of both an "up" road and a "down" road including one of said track portions, a manual road-making means common to said "up" and "down" roads, electromagnetic locking means adapted unless energized to prevent said road-making means from being so operated as to permit the passage of a train over said "up" road or "down" road, and means adapted to cause said electromagnetic locking means to be energized only when all said electro-responsive devices pertaining to said "up" road or all said electro-responsive devices pertaining to said "down" 55

road are energized, substantially as described.

19. Track apparatus for the electrical control of trains on joining track portions comprising a source or sources of electricity, traffic-controlling electro-responsive devices constituting a first set connected to rails of the track portions respectively and adapted to be energized by electricity from said source or one or more of said sources and to be de-energized when disconnected from such energizing source or sources or when short-circuited therefrom, as by conductively connected wheels of a railway vehicle, an insulation located in each rail portion joining opposite sides of a track portion, a traffic-controlling electro-responsive device of a second set bridging each said insulation and adapted to be de-energized on the failure of the corresponding insulation, for testing and making both an "up" road and a "down" road including one of said track portions, switching means adapted for use by a signalman and in one set of positions to test and make said "up" road and in another set of positions to test and make said "down" road, in one position of each of said sets disconnecting said energizing source or sources from the pertinent electro-responsive devices so as to de-energize them, in another position connecting said energizing source or sources with the last mentioned electro-responsive devices so as to energize them, and in yet another position connecting said electromagnetic points-moving means with said source or one or more of said sources and thus energizing said electromagnetic points-moving means, electromagnetic locking means adapted unless energized to prevent said switching means from being moved into the last mentioned position, and means adapted to cause said electromagnetic lockings means to be energized only when all the pertinent electro-responsive devices are energized, substantially as described.
20. Track apparatus for the electrical control of trains on joining roads one of which includes a set of sections none of which forms part of the other road and which are separated from each other by an insulation or insulations, comprising a source or sources of electricity, traffic-controlling electro-responsive devices constituting a first set and respectively connected to rails of the sections of each road, each of said insulations being bridged by one of said electro-responsive devices, an insulation located in each rail portion joining opposite sides of a road, a traffic-controlling electro-responsive device of a second set bridging each last mentioned insulation, a source or sources of electricity, and a circuit including said source of electricity or one or more of said sources and, in series, all said traffic-controlling electro-responsive devices of said first set connected with said set of sections and each traffic-controlling electro-responsive device of said second set bridging an insulation in the rails of said set of sections, each traffic-controlling electro-responsive device of said first set being adapted to be energized by electricity from said source or said one or more of said sources and to be de-energized when disconnected from such energizing source or sources or when short-circuited therefrom, as by conductively connected wheels of a railway vehicle, and each traffic-controlling electro-responsive device of said second set being adapted to be de-energized on the failure of the corresponding insulation, substantially as described.
21. Track apparatus for the electrical control of trains on track portions joined together by points comprising a source or sources of electricity, traffic-controlling electro-responsive devices constituting a first set connected to rails of the track portions respectively and adapted to be energized by electricity from said source or one or more of said sources and to be de-energized when disconnected from such energizing source or sources or when short-circuited therefrom, as by conductively connected wheels of a railway vehicle, an insulation located in each rail portion joining opposite sides of a track portion, a traffic-controlling electro-responsive device of a second set bridging each said insulation and adapted to be de-energized on the failure of the corresponding insulation, electromagnetic points-moving means adapted when

energized to move said points so as to make for a train both an "up" road and a "down" road including one of said track portions, switching means adapted for use by a signalman and in one set of positions to test and make said "up" road and in another set of positions to test and make said "down" road, in one position of each of said sets disconnecting said energizing source or sources from the pertinent electro-responsive devices so as to de-energize them, in another position connecting said energizing source or sources with the last mentioned electro-responsive devices so as to energize them, and in yet another position connecting said electromagnetic points-moving means with said source or one or more of said sources and thus energizing said electromagnetic points-moving means, electromagnetic locking means adapted unless energized to prevent said switching means from being moved into the last mentioned position, and means adapted to cause said electromagnetic lockings means to be energized only when all the pertinent electro-responsive devices are energized, substantially as described.

22. Track apparatus for the electrical control of trains on joining roads one of which includes a set of sections none of which

forms part of the other road and which are separated from each other by an insulation or insulations, comprising a source or sources of electricity, traffic-controlling electro-responsive devices constituting a first set and respectively connected to rails of the sections of each road, the or each said insulation being bridged by one of said electro-responsive devices, an insulation located in each rail portion joining opposite sides of a road, a traffic-controlling electro-responsive device of a second set bridging each last mentioned insulation, a source or sources of electricity, a circuit including said source of electricity or one or more of said sources and, in series, all said traffic-controlling electro-responsive devices of said first set connected with said set of sections and each traffic-controlling electro-responsive device of said second set bridging an insulation in the rails of said set of sections, and a circuit adapted to supply clearance current to per-

mit a train to travel along the road including said set of sections, and including said source or one or more of said sources and, 25 in series, rails of the sections of said set of sections and of the remainder of the road including said set of sections, each traffic-controlling electro-responsive device of said first set being adapted to be energized by 30 electricity from said source or one or more of said sources and to be de-energized when disconnected from such energizing source or sources or when short-circuited therefrom, as by conductively connected wheels of a 35 railway vehicle and each traffic-controlling electro-responsive device of said second set being adapted to be de-energized on the failure of the corresponding insulation, substantially as described. 40

Signed at Hove, Sussex, England, this fifth day of September 1921.

ARTHUR REGINALD ANGUS.
